(57) CLAIM

The ornamental design for the table, as shown and described.

DESCRIPTION

FIG. 1 is a perspective view of a table in accordance with the new design;

FIG. 2 is a top view thereof;

FIG. 3 is a front elevational view thereof;

FIG. 4 is a right side view thereof;

FIG. 5 is a front view of an alternative embodiment of said new design showing two portions broken away for indeterminate height;

FIG. 6 is a perspective view of an alternative embodiment of said new design; and,

FIG. 7 is a perspective view of an alternative embodiment of said new design.

The broken lines in the figures are for illustrative purposes only and form no part of the claimed invention.
